(57) **CLAIM**

The ornamental design for a vacuum cleaner for swimming pools, as shown and described.

DESCRIPTION

FIG. 1 is a front elevation view showing my new vacuum cleaner for swimming pools design;

FIG. 2 is a rear elevation view thereof;

FIG. 3 is a left-side elevation view thereof;

FIG. 4 is a right-side elevation view thereof;

FIG. 5 is a top view thereof;

FIG. 6 is a bottom view thereof; and,

FIG. 7 is a front, left-side perspective view thereof.

The broken lines illustrate non-claimed subject matter that forms no part of the claimed design.

1 Claim, 6 Drawing Sheets
